UNITED STATES PATENT OFFICE.

GUY T. GIBSON, OF NEW ROCHELLE, NEW YORK, ASSIGNOR TO GUY T. GIBSON, INC.,
OF NEW YORK, N. Y., A CORPORATION OF NEW YORK.

DESIGN FOR A FACE-POWDER BOX.

Application filed May 17, 1926. Serial No. 17,753. Term of patent 14 years.

To all whom it may concern:

Be it known that I, GUY T. GIBSON, a citizen of the United States, residing in New Rochelle, in the county of Westchester and State of New York, have invented a new, original, and ornamental Design for a Face-Powder Box, of which the following is a specification, reference being made to the accompanying drawing, forming part thereof, in which:—

Fig. 1 represents a top view of a box showing my new design.

Fig. 2 is a side view of the same.

I claim:

The ornamental design for a face powder box as shown.

GUY T. GIBSON.
